SLIDABLE JAW WRENCH

Wayne K. Bergman, 927 Butler St., Toledo, Ohio

Filed May 2, 1963, Ser. No. 74,717

Term of patent 14 years

(Cl. D54—16)

Fig. 1

Fig. 3

FIGURE 1 is a perspective view of a slidable jaw wrench taken from the side and slightly below showing my new design; and

FIGURE 2 is a perspective view thereof taken from the side and slightly above.

FIGURE 3 is a top plan view of the slidable jaw wrench.

The undisclosed side of the slidable jaw wrench is the same in appearance as the side shown.

I claim:

The ornamental design for a slidable jaw wrench, as shown and described.
